UNITED STATES PATENT OFFICE.

WILLIAM W. McCAY, OF CHICAGO, ILLINOIS, ASSIGNOR OF ONE-HALF TO WALTER R. SAMPSON, OF CHICAGO, ILLINOIS.

RAIL-JOINT.

1,278,489.

Specification of Letters Patent. Patented Sept. 10, 1918.

Application filed May 4, 1918. Serial No. 232,517.

To all whom it may concern:

Be it known that I, WILLIAM W. McCAY, a citizen of the United States, residing at Chicago, in the county of Cook and State of Illinois, have invented new and useful Improvements in Rail-Joints, of which the following is a specification.

This invention relates to devices for fastening together the meeting ends of railway 10 rails, and its object is to provide a novel and improved rail joint which is simple, strong and durable, the parts which make up the joint being so constructed and arranged that they can be easily assembled.

15 The object stated is attained by means of a combination and arrangement of parts to be hereinafter described and claimed, and in order that the same may be better understood, reference is had to the accompanying 20 drawings forming a part of this specification.

Figure 1 is a side elevation of the joint; Fig. 2 is a cross-section on the line 2—2 of Fig. 1; Fig. 3 is a side elevation of the joint 25 with one of the fish plates removed; Fig. 4 is a perspective view of the adjacent ends of the two rail sections; Fig. 5 is a side elevation of a fragment of one of the rail sections; Fig. 6 is a perspective view of one of 30 the fish plates, and Fig. 7 is a perspective view of the other fish plate, partly broken away.

Referring specifically to the drawings, 10 and 11 respectively, denote fragments of two 35 adjoining rail sections. At the meeting ends of these sections, their webs are recessed to receive web blocks on two fish plates 12 and 13, respectively, extending across the joint on opposite sides of the rails 40 and secured by bolts 14 as usual.

The web 10^a of the rail 10 is cut away at the rail base 10^b for some distance inward of the rail end, but the cut does not extend as far up as the rail head 10^c which leaves a 45 short portion 10^d of the web overhanging the recess. The bottom edge 10^e of this overhanging portion of the web is horizontal and at its inner end is a short vertical web edge 10^f from which the web edge extends to the 50 rail base 10^b with an inclination, as shown at 10^g, to produce a further overhang or undercut. One side of the web portion 10^d is cut away to produce a recess 10^h extending inward of the rail end as far as the shoulder 55 produced by the edge 10^f.

The web 11^a of the rail 11 is shaped in every way similar to the web of the rail 10, but reversed, so that when the two rail sections are assembled end to end, there is produced a recess across the joint in which seat 60 the web blocks on the fish plates 12 and 13, to be presently described. The recess is described as being formed by cutting away certain portions of the rail, but it will be understood that the rail may be rolled or 65 otherwise fashioned in the desired shape.

On the inner face of the fish plate 12 is an integral block 12^a which is shaped to seat in the lower portion of the recess hereinbefore described. This block extends up as high as 70 the bottom of the web edges 10^f and its ends are beveled, as shown at 12^b to fit the inclines 10^g. In the space in the recess not occupied by the block 12^a seats a flange 13^a extending laterally from the bottom of a 75 block 13^b seating in the portions 10^h of the recess. This block is on the inner face of the fish plate 13 and its bottom edge seats on top of the block 12^a when the latter is in place.

By the structure hereinbefore described a 80 strong and durable rail joint is provided. The rails are so securely held that spreading tendency is reduced to a minimum. The web blocks on the fish plates provide a reinforcement for the same effectually resisting all 85 tendency to distortion from side strain. The joint is simple and smooth and it involves no extra or loose parts. It will also be seen that the joint can be easily assembled, and the fastening of the rails involves no more 90 labor than a joint made with ordinary fish plates.

I claim:

1. The combination with the meeting ends of adjacent rail sections; of fish plates extending across the joint, said fish plates having web blocks on their inner faces located at different heights with respect to each other with one block seating on the other, the ends of the rail sections having recessed 100 webs in which the blocks seat, the rail webs also having a recess in one of their faces, and one of the web blocks having a portion seating in said recess.

2. The combination with the meeting ends 105 of adjacent rail sections; of fish plates extending across the joint, one of the fish plates having a web block on its inner face terminating short of the top thereof, and the other fish plate having a web block ex- 110

tending downward from the top thereof and terminating short of the bottom, with an outstanding flange seating on the first mentioned web block, the ends of the rail sections 5 having recessed webs in which the first mentioned block and the flange seat, and said webs also having a recess on one side in which the second mentioned block seats.

3. The combination with the meeting ends 10 of adjacent rail sections; of fish plates extending across the joint, one of the fish plates having a web block on its inner face terminating short of the top thereof, and the other fish plate having a web block ex-

tending downward from the top thereof and 15 terminating short of the bottom, with an outstanding flange seating on the first mentioned web block, the ends of the rail sections having recessed webs in which the first mentioned block and the flange seat, and said webs also having a recess on one side in which the second mentioned block seats, the ends of the first mentioned web block being 20 beveled, and the adjacent wall of the web recess being correspondingly undercut.

25

In testimony whereof I affix my signature.

WILLIAM W. McCLAY.
